CLAIM

The ornamental design for a display screen or portion thereof with a graphical user interface as shown and described.

DESCRIPTION

The FIGURE is a front view of a display screen or portion thereof with a graphical user interface showing the claimed design.

The outer broken lines illustrate a display screen that forms no part of the claimed design. The remaining broken lines are included for the purpose of illustrating portions of the graphical user interface that form no part of the claimed design.

1 Claim, 1 Drawing Sheet
